UNITED STATES PATENT OFFICE.

JOSEF MUCHKA, OF VIENNA, AUSTRIA, ASSIGNOR TO THE FIRM SOCIÉTÉ D'EXPLOITATION DES POMPES DABEG, OF PARIS, FRANCE.

BOILER FEED-WATER APPARATUS.

Application filed October 24, 1922. Serial No. 596,661.

To all whom it may concern:

Be it known that I, JOSEF MUCHKA, a citizen of the Republic of Austria, residing at VI, Wallgasse 39, Vienna, Austria, have 5 invented Improvements in and Relating to Boiler Feed-Water Apparatus, of which the following is a specification.

For the operation of steam engines, which are to run with variable speeds of revolution, such for instance as those of locomotives, it has been found preferable, more particularly where feed-water heaters are used, to supply the boiler with as much feed-water as is necessary to compensate for 15 the steam consumption of the locomotive.

The well-known locomotive feed pumps of the type operated from a moving part of the engine, hereinafter referred to as engine driven pumps, have the disadvantage that 20 with them the supply of feed-water can only be regulated in dependence on the speed of the locomotive, i. e. on the revolutions of the wheels, the delivery increasing with the stroke of the engine in such a manner, that 25 the pump reaches its greatest output when the engine makes the greatest number of strokes, the result being that, since the boiler output of a locomotive and consequently the demand made on the boiler does not increase 30 with the increase in the number of strokes, too much water is fed into the boiler, when the number of strokes of the engine is great. Such a method of regulation is, however, not adequate for the operation of the boilers 35 of steam engines, which with a constant speed work with a variable cut-off and therefore with a variable steam consumption.

The present invention consists in an apparatus for supplying feed-water to the boilers of steam engines operating with a variable cut-off, and is characterized by means for varying the quantity of water delivered by the pump or pumps to the boiler in accordance with the cut-off of the engine. Thus 45 the invention permits engine driven pumps to be employed, i. e. pumps operated from the valve gear of the engine. With the invention, at any speed of the engine or locomotive wheels, a regulation of the quantity 50 of water fed into the boiler may be effected, depending on the cut-off and the load on the boiler at any time.

In the accompanying drawing: Fig. 1 is a diagrammatic view of a structural example

of an arrangement according to the invention, in which the boiler feed-water is injected from the tender by means of a cold water pump into a condenser for condensing the exhaust steam, from which the oil has been removed, and the hot water and condensate is forced into the boiler by means of a hot water pump. Fig. 2 is a diagrammatic sectional view on an enlarged scale of a valve forming part of the structure, the valve being in one of its open positions. Fig. 3 is a similar view with the valve closed. Fig. 4 is a detail sectional view of another valve forming part of the apparatus.

1 is a cold water pump, which is connected on the one hand by the suction pipe 2 to the tender 3 and on the other hand by the delivery pipe 4 to a jet condenser 5 on the boiler 14. The cold water pump 1 coacts with a hot water pump 6, which is connected by the suction pipe 7 to the jet condenser 5 and by the delivery pipe 8 to the boiler and conveys the hot water and condensate from the jet condenser into the boiler. The two pumps are constructed as engine driven pumps, i. e. they are operated directly from the valve gear of the locomotive, for instance by an eccentric disc 9, which operates the valve gear.

In order to obtain an automatic regulation of the quantity of water delivered by the pump into the boiler in dependence on the output or cut-off of the locomotive at any time, in the constructional example of the drawing there is provided a by-pass 11 from the delivery pipe 4 of the cold water pump, which pipe 11 opens into the tender, and which is capable of being shut off completely or partially from the main pipe 4 by a regulating member 12 (slide, valve, cock or the like). Fig. 2 shows the valve 12 in the zero or middle position of control. In this position, all the water drawn in by the cold water pump 1 is delivered by pipe 11 back into the tender 3. The valve includes an outer rotary plate and an inner stationary plate. The inner plate has eight holes 12^a and the outer plate has only four apertures 12^b. Fig. 3 shows the valve 12 in the position in which the water drawn in by the cold water pump is delivered by pipe 4 into the condenser and into the boiler. In the full open position of the control lever of the engine, the valve 12 is in the same position

as shown in Fig. 2, and all the water drawn in by the cold water pump is delivered by pipe 11 back into the tender 3, and the delivery of water into the boiler is interrupted.

5 As is well known, the control lever is in the full open position only for starting and for running idle, and the starting lasts only a very short time. During this short period of time, all precautions must be taken to prevent the pressure within the boiler from lowering, and for this reason the valve 12 is arranged to interrupt the delivery of water into the boiler, during starting. The member 12 is connected to the reversing shaft 13 of the locomotive in such a manner that, according to the position of the valve gear, i. e. according to the steam admitted to the steam cylinder, the quantity of water sucked by the pump 1 is either wholly or 10 only partially or not delivered into the boiler. The arrangement is such, as before stated, that the regulating member 12, which is coupled with the reversing shaft 13, shuts off the branch pipe 11 entirely or opens it more or less, whereby a portion of or all the water can be passed through the branch pipe 11 into the water vessel 3.

15 The feed-water pump is constructed to deliver to the boiler at each stroke a quantity of water equal to the quantity which, converted into steam, must be supplied by the boiler to the engine during each stroke of the engine piston or pistons, when the engine is under maximum load, this maximum quantity being reached at a definite cut-off. The regulating-member connected to the valve-gear is adjusted so that the whole of the water delivered by the pump can be passed into the boiler. At earlier cut-offs than that corresponding to the maximum load on the locomotive, the regulating member allows the water sucked up by the pump in excess of the quantity required to replace the steam taken by the engine at the particular cut-off, to pass away. As the amount of water which flows into the boiler during each stroke of the feed-water pump and of the engine corresponds approximately to the steam consumption, these quantities 20 will thus be approximately equal at every speed of revolution of the wheels, consequently at all engine speeds. For later cut-offs than that corresponding to the greatest load on the locomotive, a portion of the water sucked up will also be led away, because, in practice notwithstanding the later cut-off, the output of the engine will be smaller in that the engine can only be driven at such cut-offs with a nearly closed throttle. When the valve gear is in the full admission and mid gear positions, no water is delivered to the boiler, and the whole of the water is led away by the regulating member. The shutting off of the water supply to the boiler at full admission is necessary chiefly

for the reason that, when the locomotive is starting or running light (in which case, the motion is in full gear), no cold water must be fed to the boiler.

When the delivery pipe 4 is open, any variation in the pressure in the condenser 5 reacts on the pump. If the pressure in the space 5 rises, the liquid which passes out of the delivery pipe of the pump 1 acts against a greater pressure than it does when the pressure in the space 5 falls. The liquid will, therefore, be forced out of the delivery pipe 4 at a greater or less pressure. If, however, the delivery pipe is provided with a branch pipe 11, then a rise in pressure in the space 5 will have the effect of permitting less water to pass out of the delivery pipe 4 than at lower pressure, because the liquid takes the path of least resistance, i. e., through the pipe 11.

To make the outflow of liquid from the delivery pipe 4 independent of the pressure existing in the space 5, a regulable resistance is inserted in the delivery pipe. This resistance is considerably greater than the maximum pressure which may exist in the space 5; consequently, a regular action of the pump is obtained, and substantially the same quantity of water can always flow out through the delivery pipe 4, irrespective of the intensity of pressure in the space 5. The resistance may consist of a spring-loaded valve 15, which is adapted to close the outlet end of the delivery pipe 4 of the pump, the spring being adjusted so that the load on the valve is greater than the maximum pressure which may exist in the space 5. It is of course, not necessary to close the outlet end of the pipe 4 by means of a valve; because a resistance which would act in the same manner may be inserted inside said pipe.

From the foregoing it is believed that the construction, operation and advantages of the invention may be readily understood and it is apparent that changes may be made in the details disclosed without departing from the spirit of the invention as expressed in the claims.

What I claim is:

1. The combination with a steam-engine operating with a variable cut-off, an engine boiler, and a valve gear for the engine, of apparatus for supplying feed water to the engine-boiler, comprising a feed-water forcing device and means, controlled by the valve gear of the engine, for varying the quantity of water delivered by the feed-water forcing device to the boiler in accordance with the cut-off of the engine.

2. The combination with a steam-engine operating with a variable cut-off, an engine boiler, and a valve gear for the engine, of apparatus for supplying feed water to the engine-boiler, comprising a feed-water pump

and means, controlled by the valve-gear of the engine, for varying the quantity of water delivered by the pump to the boiler in accordance with the cut-off of the engine.

5 3. The combination with a steam-engine operating with a variable cut-off, an engine boiler, and a valve gear for the engine, of apparatus for supplying feed water to the engine-boiler, comprising a feed-water pump 10 and a regulating member in one of the pipes of the pump, and controlled by the valve-gear of the engine, for governing passage of liquid through said pipe, so arranged that, at the cut-off corresponding to the greatest 15 output of the engine, the maximum quantity of water is delivered to the boiler, this quantity being greater than that delivered at earlier or later cut-offs, and that, in the full admission position of the valve-gear, no 20 water passes through said delivery pipe.

4. The combination with a steam-engine operating with a variable cut-off, an engine boiler, and a valve gear for the engine, of apparatus for supplying feed water to the 25 engine-boiler, comprising a feed-water pump operated from a moving part of the engine, and means, controlled by the valve-gear of the engine, for varying the quantity of water delivered by the pump to the boiler, in accordance with the cut-off of the engine.

5. The combination with a steam-engine operating with a variable cut-off, an engine boiler, and a valve gear for the engine, of apparatus for supplying feed water to the 30 engine-boiler, comprising a feed-water pump having a delivery pipe, means, controlled by the valve-gear of the engine, for varying the quantity of water delivered by the pump to the boiler in accordance with the cut-off of the engine.

the engine, and a resistance device in said 40 delivery pipe for maintaining the pressure therein above that existing in the space into which the water is delivered by the pump.

6. The combination with a steam-engine operating with a variable cut-off, an engine boiler, and a valve gear for the engine, of apparatus for supplying feed water to the engine-boiler, comprising a feed-water pump having a delivery pipe, means, controlled by the valve-gear of the engine, for varying the 45 quantity of water delivered by the pump to the boiler in accordance with the cut-off of the engine, and a spring-loaded valve in said delivery pipe for maintaining the pressure 50 therein above that existing in the space into which the water is delivered by the pump.

7. The combination with a steam-engine operating with a variable cut-off, an engine boiler, and a valve gear for the engine, of apparatus for supplying feed water to the 55 engine-boiler, comprising a feed-water pump having a delivery pipe, a by-pass from said pipe, and means, controlled by the valve-gear of the engine, for governing passage of liquid through said delivery-pipe and said by-pass, so arranged that, at the cut-off corresponding to the greatest output of the engine, the maximum quantity of water is delivered to the boiler, this quantity being greater than that delivered at earlier or later cut-offs, and that, in the full admission position of the valve-gear, no water passes through said delivery pipe, but only through said by-pass.

In witness whereof I have hereunto signed my name.

JOSEF MUCHKA.
